UNITED STATES PATENT OFFICE.

EZRA J. PACKER, OF PHILADELPHIA, PENNSYLVANIA, ASSIGNOR TO THE POOLEY COMPANY, OF PHILADELPHIA, PENNSYLVANIA, A CORPORATION OF PENNSYLVANIA.

RADIOAMPLIFIER AND SUPPORT.

Application filed January 24, 1925. Serial No. 4,363.

To all whom it may concern:

Be it known that I, EZRA J. PACKER, a citizen of the United States, residing at Philadelphia, county of Philadelphia, and

5 State of Pennsylvania, have invented a new and useful Improvement in Radioamplifiers and Supports, of which the following is a full, clear, and exact description, reference being had to the accompanying drawings, which form a part of this specification.

10 My invention relates to cabinets for containing a radio receiving outfit and particularly to the construction and mode of suspension of the amplifier that is connected with the loud speaker.

15 A preferred embodiment of the invention is shown in the accompanying drawings, in which:—

20 Fig. 1 is a perspective view of the cabinet, looking toward the front.

Fig. 2 is a sectional view of the cabinet on line 2—2, Fig. 1, showing the amplifier in plan.

25 Fig. 3 is a perspective view of the amplifier and its immediate supporting means, looking toward the rear.

Fig. 4 is a vertical section through the amplifier on line 4—4, Fig. 2.

30 Fig. 5 is a perspective view of the amplifier with the wooden horn removed.

Fig. 6 is a detail view of a part of the amplifier supporting means.

35 The cabinet *a* may be of any desired construction. The cabinet shown contains a shelf or compartment for the reception of all the elements of the radio except the aerial and the loud speaker. The loud speaker *b* is secured to the sound-receiving end of the amplifier. The construction of the radio and the mechanical and electrical connections between the parts thereof are not herein shown, as my invention is entirely independent thereof.

40 The amplifier is formed of three parts, namely: a metal horn *c* whose internal diameter progressively increases from its sound-receiving end to its sound-discharge end; an intermediate wooden block, preferably L-shaped, which may be made, if desired, in two sections which are hollowed out to form a sound-conveying channel of gradually expanding cross section; and a sound-exit horn *f* having four wooden walls (one at least of which should be laminated)

forming a sound-discharge-mouth of gradually expanding cross section, the laminated wall *g* thereof being preferably concavely curved toward the sound-discharge opening.

45 Block section *d* of the intermediate part of the amplifier is hollowed out to form a sound-conveying channel, the entrance of which is a circular opening aligning with the sound-discharge end of the metal horn, and the exit of which is of rectangular shape (preferably about square) and of substantially greater cross-sectional area than the cross-sectional area of the entrance of the channel. The metal horn *c* is provided with an annular flange *c'* which is secured to the face of the block surrounding the circular entrance to its sound-conveying channel. The metal horn *c* is preferably supported, between its ends, by means of an upright *t* secured to the outside of the section *e* of the intermediate block.

50 Block section *e* of the intermediate part of the amplifier is hollowed out from one side to form a concave internal wall which expands toward the rectangular-shaped exit of the sound-conveying channel in section *d*. The top and bottom walls of the sound-conveying channel in section *e* are preferably flat. The exit mouth of the sound-conveying channel in section *e* is of 55 oblong shape, its shorter vertical height corresponding to the height of the exit end of the channel in section *d*, so that the cross-sectional area of its sound discharge opening is somewhat greater than the cross-sectional area of the sound-discharge opening 60 of section *d*. Thereby the sound conveying channel continues to expand in its course through section *e*.

65 Block sections *d* and *e* are made separately merely as a manufacturing expedient to facilitate coring them out. They may be made in one piece if desired.

70 The sound-inlet opening and sound-exit opening of the upright leg *d* of the L-shaped block are located on the same face of the upright leg and the metal horn *c* extends from the upper or sound-inlet opening above and parallel to the direction of extension of the horizontal leg *e* of the L-shaped block. The wooden horn *f* extends from the side of the horizontal leg *e* of the L-shaped block, its axis extending at right angles to the direction of extension of the axis of the metal horn.

It is found that the vibrations produced by the amplifier are transmitted to the cabinet and thence to the radio apparatus, resulting in imperfect functioning of certain 5 of its elements. I find that this objectionable transmission of vibrations is avoided by supporting the amplifier as shown on the drawings.

The cabinet is provided, along the front, 10 with a beam *m* and along the rear with a beam *n*. The sections *d* and *e* of the intermediate channelled block rest on rubber cushions *o* or other elastic supports, which in turn rest on rear beam *n*. A screw *p* extends 15 through the beam *n* and each cushion into the block *d*, *e*. The lower wall of the horn *f* also rests, near its front edge, on similar rubber cushions *o'*, which are secured between the beam *m* and the lower 20 wall of the horn by means of screws *p'*. These rubber cushions are, in effect, "vibration insulators" and the amplifier a "floating" amplifier.

The amplifier does not require any additional support after the cabinet is set in place for use; but for purposes of transportation, it is safer to secure the rear face of section *d* of the intermediate block to an upright *r* secured to the rear of the cabinet, and 30 (in order to avoid transmission of vibrations) separate the upright from block section *e* by means of rubber cushions *o*² similar to cushions *o* and *o'*, and screws *p*² similar to screws *p* and *p'*.

35 What I claim is:

1. A sound amplifier comprising a metal horn, an intermediate wooden block and a wooden horn; the intermediate block being formed in two sections, one section being 40 hollowed out to form a channel extending successively inward, downward and outward and providing a sound-entrance and sound-exit located on the same face of the section, the sound entrance communicating with the 45 metal horn, the other section being hollowed out to form a chamber having a curved wall

overhung and underhung by flat walls and providing a sound-entrance opening communicating with the sound-exit opening of the first section and a sound-exit opening communicating with the sound-entrance opening of the wooden horn.

2. The combination with a cabinet adapted to contain a radio-receiving outfit; of a sound amplifier comprising a block having a member extending lengthwise of the cabinet and an upright member and hollowed out to form a sound conduit extending through both members and having a sound entrance opening in the side of the upright member and a sound exit opening in the front of the lengthwise extending member, a sound-receiving horn supported by said block and extending above and along its lengthwise extending member and communicating with said sound entrance opening, and a sound-discharge horn communicating with said sound exit opening and extending forwardly across the cabinet, and means on the cabinet supporting said block and sound-discharge horn.

3. The combination with a sound amplifier comprising a metal horn, an intermediate channelled wooden block, and a wooden horn; of a cabinet adapted to contain a radio-receiving outfit and comprising amplifier supporting beams at front and rear, said block overlying one of said beams and the outer end of the wooden horn overlying the other of said beams, and elastic vibration insulators between said beams and said block and wooden horn, whereby the sound amplifier is held in floating relation to the cabinet, thereby minimizing transmission to the radio outfit of vibrations produced by the passage of sound waves through the amplifier.

In testimony of which invention, I have hereunto set my hand, at Philadelphia, Pennsylvania, on this 22nd day of December, 1925.

REED M. COOPER
